ATTORNEY.

UNITED STATES PATENT OFFICE.

JOHN C. UNDERWOOD, OF COLUMBUS, OHIO.

DESIGN FOR A BADGE.

SPECIFICATION forming part of Design No. 19,194, dated July 2, 1889.

Application filed May 31, 1889. Serial No. 312,807. Term of patent 3½ years.

To all whom it may concern:

Be it known that I, JOHN C. UNDERWOOD, of the city of Columbus, county of Franklin, State of Ohio, have invented and produced a 5 new and original Design for a Badge, of which the following is a full, clear, and exact specification.

My newly-designed badge is fully illustrated in the accompanying drawing, to which reference is made. The base is of suitable material, with the representation of an olive-wreath border. On this base there is a six- 10 armed star of Maltese pattern. Resting on this is a six-pointed star, the points of the star resting on the arms of the star of Maltese pattern. In 15 the center of the pointed star there is a raised disk. The badge is pendent from a pin of three links.

I claim—

The design for a badge herein shown and 20 described.

JNO. C. UNDERWOOD.
